UNITED STATES PATENT OFFICE.

JOSEPH S. DUNCAN, OF CHICAGO, ILLINOIS, ASSIGNOR, BY MESNE ASSIGNMENTS, TO ADDRESSOGRAPH COMPANY, OF CHICAGO, ILLINOIS, A CORPORATION OF DELAWARE.

PRINTING MACHINE.

Application filed July 23, 1927. Serial No. 207,981.

This invention relates to printing machines of that type wherein printing devices for printing addresses or other matter are run from a stack one at a time through printing 5 position and it has for its primary object to provide means for distributing impressions from parts of the printing device in separate column spacings on a sheet.

The present invention is particularly useful in preparing pay rolls, tax data, subscription records, factory records and for a great many other purposes where a list is desired having certain data on separate lines or on 10 separate columns as, for example, to have the name and the address on the same line but in 15 separate columns.

Another important object of the invention is to provide a machine which will carry the sheet to be printed bodily in two different 20 directions to dispose the paper with respect to the printing device so that parts of the printing form will be printed on the same line and in different columns on the sheet.

A further object of the invention is to provide 25 a machine with intermittently operated platens and sheet carrying means correlated to print parts of the form of a printing device on the same line and in separate columns on the sheet.

30 And a further object is to provide a machine which is compact and simple in construction, and which operates automatically for causing certain lines of a printing device form to be printed intermittently on a sheet, and in predetermined positions both horizontally and vertically.

The accompanying drawings illustrate a 35 machine embodying this invention and the views therein are as follows:

40 Fig. 1 is a front elevation of the machine.
Fig. 2 is a longitudinal vertical section through the machine.

Fig. 3 is a detail plan view.

Fig. 4 is a transverse vertical section.

45 Fig. 5 is a detail vertical section taken on the line 5—5 of Fig. 3.

Fig. 6 is a detail view of the paper securing means.

50 Figs. 7 and 8 are detail sectional views taken through the center of the machine and show the alternate printing position of the platens.

Fig. 9 is a plan view of a printing device

of a type which may be used in connection with this invention.

Figs. 10^a, 10^b and 10^c are diagrammatic 55 views of a sheet of paper showing the various steps of the printing operation.

Referring to the drawings 1 designates a suitable frame which supports a drive shaft 2 driven in any suitable manner as by an electric motor, (not shown). A bevel gear 3 is mounted on the drive shaft and it meshes with another bevel gear 4 fixed on a transverse shaft 5. An arm 6 is fixed on the shaft 5 and rotatable therewith. A casing 7 is 60 mounted on the top of the frame which supports a horizontal rod 8 which operates the platen mechanism. A short shaft 10 is secured in the end 9 of the casing 7 and carries a loosely mounted member 11. A rod or arm 12 has one end thereof connected to one edge of the member 11, Figs. 2 and 5 and the other end to one edge of the arm 6. Through this connection rotation of the drive shaft 2 causes oscillatory movement of the member 75 11.

A yoke 13 is loosely arranged on the shaft 10 and straddles the member 11 as shown in Fig. 3. A plate 14 is loosely mounted on the shaft 10. This plate has an outwardly projecting stud 15 and a stud shaft 16 arranged thereon. An arm 17 has one end pivotally mounted on the stud shaft 16 and the other end pivotally connected to a link 18 fixed on the rod 8. Through this connection 80 the motion of the plate 14 is transmitted to the rod 8. A plate 19 is loosely mounted on the shaft 10 adjacent the plate 14 and on the side opposite to the member 11. A lever 20 is pivotally mounted on the side of the casing 90 7 and extends therethrough. A rod 21 connects the plate 19 and the lever 20 together Figs. 2 and 5.

The plate 14 is preferably made triangular in shape, and the stud shaft 16, Fig. 2, is located near its apex and the stud 15, Fig. 3, is located near its base. A bar 22 is arranged on this plate and is free to pivot thereon. The bar carries a finger 23, Fig. 5, to which a spring 24 is attached to hold the bar upwardly. The finger 23 extends beyond the face of the plate 14 and on the side opposite that to which the rod 21 is fastened. A lug 25 fastened on the lower end of the member

11 projects outwardly therefrom and is free to abut against the top 26 of the bar 22. The downward movement of the member 11 causes the lug 25 to engage the bar 22, and causes the 5 plate 14 to follow that movement. A spring 27 attached to the arm 17, causes the plate 14 to return to its original or normal position. The plate 19 has a bevel edge 28, Fig. 5, and when the lever 20 is down the finger 23 is 10 free to clear the plate. However, when the lever 20 is up the beveled edge 28 of the plate 19 moves downward a sufficient distance to cause the finger 23 to contact with the beveled edge of the plate 19 and to ride thereon 15 which pulls the bar 22 away from engagement with the lug 25 on the member 11 so that the plate 14 and the rod 8 will remain idle. The lever 20 is connected to the printing device feeding means which causes the 20 lever to be raised upwardly when no devices are fed and thus prevents operation of the platen or rotation of the carrying shaft. Further explanation of the platen and carrying shaft will be made during the progress of 25 this application.

A gear 30 fixed on the drive shaft 2 meshes with a gear 31 fixed on a shaft 32 which is mounted in the frame 1 and parallel with the driving shaft 2, Fig. 2. A downwardly extending arm 33 is pivotally mounted on the frame 1 and carries two rollers 34 and 35, Fig. 1. These rollers are pivotally mounted on short shafts 36 extending outwardly and rearwardly from the arm 33 and are free to 30 revolve thereon. A cam 37, Figs. 1 and 2, adjacent the arm 33, is fixed to the gear 31 and operates between the rollers 34 and 35. Rotation of the cam causes alternate engagement with each of the rollers and moves the arm 33 35 back and forth in the direction of the high spot of the cam. Rotation of the shaft 2 therefore rotates the large gear 31 and the cam 37, and causes reciprocation or rocking movement of the arm 33.

40 A bar 39, Fig. 1, is pivotally mounted on the side of the frame at 38 and carries a yoke 40 which is rigidly fastened thereto. This yoke engages a double flanged member 41 which is fixedly secured to the carrying shaft 42. A 45 link 43 pivotally connects the bar 39 with the arm 33. Thus, reciprocation of the arm 33 causes reciprocation of the bar 39 which in turn, through its connection with the yoke 40 and the double flanged member 41, moves the carrying shaft longitudinally. The carrying shaft 42 is supported in a sleeve 44 mounted in the frame and is free to rotate therein.

A ratchet wheel 45, Figs. 2 and 3, is fixedly mounted on the carrying shaft 42, and has a 50 plurality of alternately spaced wide and narrow ratchet teeth 46 and 47. A pawl 48, Fig. 3, is pivotally mounted on an arm of the yoke 13 which is adapted to alternately engage a wide and a narrow tooth on the ratchet wheel 55 to rotate this wheel and the shaft 42. This

pawl is held down or in normal position against the ratchet by means of a spring 49 which is also attached to one of the side members of the frame. The yoke and the ratchet are timed so that rocking movement of the 70 yoke 13 causes the pawl 48 to ride on the ratchet a distance slightly greater than the width of one of the large teeth. Therefore, rocking movement of the yoke 13 moves the pawl 48 on the ratchet and alternately engages a large tooth and a small tooth which 75 rotates the carrying shaft a distance equal to either one of these teeth. When the ratchet moves the carrying shaft the distance of a small notch, it is equivalent to the distance 80 between the last line and the next to the last line of a printing device of the type shown in Fig. 9. Rotation of the carrying shaft 42 the distance of a large tooth is equivalent to the distance between the horizontal parallel 85 lines on the sheet shown in Figs. 10^a, 10^b, and 10^c. Rather than move the printing device, which would be an intricate operation and which, no doubt, would require too fine an 90 adjustment for perfect and speedy printing, it has been found preferable to move the sheet a sufficient distance to get the different lines of printing in proper lineal position on the sheet.

A reel comprising a plurality of wheels 50 95 fixedly attached to the carrying shaft 42 is adapted to support and carry a sheet which may be printed in blank as shown in Figs. 10^a, 10^b, and 10^c. Suitable braces 51 connect these wheels at intervals and keep the same in 100 spaced relation to each other, and add strength and rigidity thereto. A rod 52 extending through suitable lugs 53 formed on the wheels, and free to move therein, is provided with a plurality of pins 54, Figs. 7 and 8. A finger 55 is pivotally mounted on the rim of each of these wheels and it has an upturned edge 56 which is adapted to be engaged by the pins 54 on the rod 52. A spring 57 holds these fingers tightly against the outside edge or rim of the reel. The reel may be recessed to form a seat 58 for the fingers 55, thereby providing an even and full bearing for the fingers to properly hold the paper in 110 position. On the outer end of the rod 52 is a lever 59, Fig. 1, whereby movement thereof causes the pins 54 to engage the fingers and raise them upwardly. The spring 57 acts oppositely thereto and in normal position holds these fingers in the seats 58 in the wheels 115 50. Rollers 61 are arranged on the spokes 60 of the wheels to engage a rod 62 pivotally mounted on the carrying shaft. Longitudinal movement of the carrying shaft supports the reel on the rod 62 and causes the reel to 120 maintain its normal position at all times, throughout the entire operation of the machine.

Links 63 are fixed to the rod 8 and are 125 curved to provide clearance from the sleeve 130

44. An intermediate support 66 has a yoke 67 pivotally connected thereto near the rearward edge thereof. A platen casing 68 has a pair of upwardly disposed arms 69 which are pivotally connected to the yoke. Ears 70 struck up from the platen casing 68 are pivotally connected to the curved links 63 by means of straight links 71. A pair of arms 72 have one end pivotally connected to the frame support 66 and the other end pivoted to a rod 73 extending through the ears 70 of the platen frame. Through this mechanism oscillation or rocking movement of the rod 8 causes vertical reciprocation of the platen casing. A pair of platens 75 and 76, Figs. 7 and 8 are arranged within the platen casing and are held upwardly by spring 74. Rods 77 extend through the platen casing and are cut away to form cam faces 77' which contact with the top of the platens so that oscillation of the rods will alternate reciprocation of the platens. A pair of levers 78 are fastened to the rods 77 and are pivotally connected together by a link 79. A projection 80 integrally connected to the link 79 is adapted to be engaged by a disk 81 connected to one of the wheels 50. A spring 82 fastened to one of these levers 78 normally holds the levers in a predetermined position and causes one of the platen members to be in printing position. Upon return movement of the carrying shaft, the wheel having the disk 81 will strike the projection 80 and oscillate the rods 77 in the direction opposite to that shown in Fig. 4. This movement oscillates the rods ninety degrees and causes the platen which was in normal printing position, to be raised and causes the other platen to be lowered into printing position. 40 As the carrying shaft moves to the left, Fig. 4, the projection 80 is released and the spring 82 pulls the levers back to normal position; this operation alternates the printing position of the platens.

45 A magazine 83 is mounted on the frame, Fig. 2, and is adapted to carry a stack of printing devices which may be of the kind shown in Fig. 9. These devices are fed from the bottom of the stack by means of a chain 84 carried by suitable sprockets 85. The chain has suitable projections 86 fastened thereto at intervals which take a printing device from the bottom of the stack and carry it along to printing position underneath the platen. The chain and the carrying mechanism is operated in any suitable manner as is well known in the art and no further description thereof is required in this application.

60 A pair of longitudinal members 87 and 88 having bevelled outer ends 89 and 90 are arranged in the casing 7, Fig. 4, and held in normal position by set screws 91; the rod 8 extends through the lower longitudinal member 88 and is free to move vertically therein.

These members permit vertical adjustment of the rod 8 to accommodate reels of different sizes for sheets of different sizes. Adjustment is obtained by loosening the set screws 91 and adjusting the set screw 92 to move the member 87 relative to the member 88 after which the set screws 91 are again tightened to lock the members in adjusted position, and the nut 93 is adjusted to lock the screw 92. In practice, a blank sheet as shown in Fig. 75 10^a is placed on the reel and held thereon by means of the clamping members 55, and the machine is placed in operation. The reel carries the sheet into printing position to receive an impression from a part of the form 80 of the printing device in one column as shown in Fig. 10^b. Then the reel moves longitudinally and circumferentially to carry the sheet into printing position to receive an impression and another part or all the rest of the 85 printing form on the sheet in another column but on the same line with the first impression, as shown in Fig. 10^c. When impressions have been made from all parts of the printing devices to be printed the reel moves longitudinally and circumferentially, and returns to initial position, which is first impression position, with a portion of the sheet in printing position to receive a part of the next printing device in the first column to be 95 printed and on the next line. At the same time a new printing device is fed into printing position and this completes one cycle of operation of the machine.

In Fig. 9 I have shown a printing device 100 having a form which comprises on one line the name of a person, on the next line his occupation, and on the third line certain personal information with respect to the person. A sheet is printed in blank to receive the information on the printing device in a certain desired arrangement which, in the example shown, involves printing the third information line in the first printing operation as 105 shown in Fig. 10^b, and the first and second lines of the printing device forms are printed at the same time in the next operation in the adjacent column with the impression of the second line of the printing device form aligned with the impression of the third line 115 of the printing device form, as shown in Fig. 10^c. This is a simple example of the use of my invention and it is selected for convenience in describing the invention and not to limit the invention to printing a particular number 120 of lines in any particular number of columns.

Changes in the form, construction and arrangement of parts of the invention may be made without departing from the spirit or sacrificing any of the advantages thereof and 125 I reserve the right to make all such changes as fall within the scope of the following claims.

I claim:

1. A printing machine comprising a frame, 130

a shaft supported thereby, sheet carrying means secured to said shaft, means for reciprocating said carrying means, and means for partially and intermittently rotating said carrying means.

2. A printing machine comprising a frame, a shaft supported thereby, sheet carrying means secured to said shaft, and means for alternately reciprocating and partially and intermittently revolving said carrying means.

3. A printing machine comprising a frame, a shaft in said frame, sheet carrying means fixed to said shaft, a platen shaft, means for reciprocating and partially and intermittently revolving said carrying means, and means for oscillating said platen shaft.

4. A printing machine comprising a frame, a shaft in said frame, sheet carrying means fixed to said shaft, a platen shaft, a platen connected to said platen shaft, means for reciprocating and revolving said sheet carrying means, and means for oscillating said platen shaft to reciprocate said platen.

5. A printing machine comprising a frame, a shaft mounted on said frame, a reel arranged on said shaft, means for revolving said shaft, means for reciprocating said shaft, means arranged on said reel for holding a sheet, a pair of platens, and means for reciprocating said platens alternately.

6. A printing machine comprising a frame, a shaft mounted on said frame, a reel arranged on said shaft, means for reciprocating said reel, means for alternately revolving said reel predetermined distances, and means for securing a sheet to said reel while the reel is at rest.

7. A printing machine comprising a frame, a shaft mounted on said frame, a reel arranged on said shaft, means for reciprocating said reel, and means for alternately revolving said reel unequal distances, a platen shaft arranged in said frame, a platen, and means operated by said platen shaft for vertically reciprocating said platen.

8. A printing machine comprising a frame, a shaft mounted on said frame, a reel arranged on said shaft, means for reciprocating said reel, means for revolving said reel alternately two unequal predetermined distances, a platen shaft arranged in said frame, a pair of platens, and means operated by said platen shaft for vertically reciprocating said platens alternately.

9. A printing machine comprising a frame, a shaft mounted on said frame, means arranged on said shaft to carry a sheet, means for feeding printing devices to impression position, and means for causing the horizontal lines of impression to print in a single line on said sheet.

10. A printing machine comprising a frame, sheet carrying means, a platen, means for feeding printing devices one at a time to printing position, means for rotating and

reciprocating the carrying means to move the sheet relative to the printing devices for causing the last line of the impressions on said printing devices to be printed in one position on the sheet, and means for causing other lines of impressions to be printed in another position on said sheet but horizontal with the first impression.

11. A printing machine comprising a frame, a shaft supported by said frame, a reel fixed to said shaft, clamps arranged on the rim of said reel for holding a sheet, a ratchet fixed to said shaft, a pawl for operating said ratchet, means for operating said pawl, means flexibly connected to the end of said shaft for reciprocating the same, a platen shaft, means for oscillating said platen shaft, a platen, means connecting said platen and said platen shaft for reciprocating said platen, and means for feeding printing devices into printing position relative to said platen.

12. A printing machine comprising a frame, a shaft supported by said frame, a reel fixed to said shaft, clamps arranged on the rim of said reel for holding a sheet, a ratchet fixed to said shaft, a pawl for operating said ratchet, means for operating said pawl, means flexibly connected to the end of said shaft for reciprocating the same, a platen shaft, means for oscillating said platen shaft, a pair of platens, means connecting said platens and said platen shaft for reciprocating said platens alternately, and means for feeding printing devices into printing position relative to said platens.

13. A printing machine comprising a frame, a shaft mounted on said frame, sheet carrying means on said shaft, a ratchet on said shaft and having a plurality of alternate large and small teeth, means for moving said ratchet one tooth at a time, means for reciprocating said shaft, a platen, means for operating said platen, means for feeding printing devices to printing position, and means controlled by said last named means to prevent operation of the platen and rotation of said shaft when printing devices are not in printing position.

14. A printing machine comprising a frame, a shaft mounted on said frame, sheet carrying means on said shaft, a ratchet on said shaft and having a plurality of alternate large and small teeth, means for moving said ratchet one tooth at a time, means for reciprocating said shaft, a pair of platens, means for reciprocating said platens alternately, means for feeding printing devices to printing position, and means controlled by said last named means to prevent operation of the platens and rotation of said shaft when printing devices are not in printing position.

15. A printing machine comprising a frame, a shaft mounted on said frame, sheet

carrying means on said shaft, a ratchet on said shaft and having a plurality of alternate large and small teeth, means for moving said ratchet one tooth at a time, means for reciprocating said shaft, a pair of platens, means for reciprocating said platens alternately, means for feeding printing devices one at a time to printing position, means controlled by said last named means to prevent operation of the platens and rotation of said shaft when printing devices are not in printing position, means connecting said sheet carrying means to hold the same in place, and a guide cooperating with said sheet carrying means to assure simultaneous operation thereof.

16. A printing machine comprising a frame, a drive shaft mounted in said frame, a driven shaft mounted in said frame, gears cooperating with said shafts, an arm loosely mounted on said driven shaft, a pair of rollers on said arm, a driven cam operating between said rollers for reciprocating said arm, a platen shaft, means operated by said driven shaft for operating said platen shaft, a carrying shaft, means arranged on said carrying shaft for holding a sheet, means operated by said arm for reciprocating said carrying shaft, means driven by said driving shaft for rotating said carrying shaft, a platen, and means connecting said platen and said platen shaft for reciprocating said platen.

17. A printing machine comprising a frame, a drive shaft mounted in said frame, a driven shaft mounted in said frame, gears cooperating with said shafts, an arm loosely mounted on said driven shaft, a pair of rollers on said arm, a driven cam operating between said rollers for reciprocating said arm, a platen shaft, means operated by said driven shaft for operating said platen shaft, a carrying shaft, means arranged on said carrying shaft for holding a sheet, means operated by said arm for reciprocating said carrying shaft, means driven by said driving shaft for rotating said carrying shaft, a plurality of platens, and means connecting said platens and said platen shaft for alternately reciprocating said platens.

18. A printing machine comprising a frame, a driving shaft mounted in said frame, a driven shaft mounted in said frame, gears cooperating with said shafts, an arm loosely mounted on said driven shaft, a pair of rollers on said arm, a driven cam operating between said rollers for reciprocating said arm, a platen shaft, means operated by said driven shaft for operating said platen shaft, a carrying shaft, means arranged on said carrying shaft for holding a sheet, means operated by said arm for reciprocating said carrier shaft, means driven by said driving shaft for rotating said carrier shaft, a plurality of platens, means connecting said platens and said platen shafts for alternately reciprocating said plat-

ens, and means for feeding printing devices one at a time to printing position.

19. A printing machine comprising a frame, a driving shaft mounted in said frame, a driven shaft mounted in said frame, gears 70 cooperating with said shafts, an arm loosely mounted on said driven shaft, a pair of rollers mounted on said arm, a driven cam operating between said rollers for reciprocating said arm, a platen shaft, means operated by 75 said driven shaft for operating said platen shaft, a carrying shaft, means arranged on said carrying shaft for holding a sheet, means operated by said arm for reciprocating said carrying shaft, means driven by said driving shaft for 80 rotating said carrying shaft, a plurality of platens, means connecting said platens and said platen shaft for alternately reciprocating said platens, means for feeding printing devices one at a time to printing position, and means operated by said feeding means for preventing operation of said platens and rotation of said carrier shaft when printing devices are not in printing position.

20. A printing machine comprising a 90 frame, a driving shaft mounted in said frame, a driven shaft mounted in said frame, gears cooperating with said shafts, an arm loosely mounted on said driven shaft, a pair of rollers on said arm, a driven cam operating between said rollers for reciprocating said arm, a casing connected to said frame, a platen shaft arranged in said casing, means operated by said driving shaft for oscillating said platen shaft, a platen, means operated by said platen shaft for reciprocating said platen, a sleeve in said casing, a sheet carrying shaft in said sleeve, means operated by said arm for reciprocating said carrying shaft, means operated by said driving shaft for intermittently rotating said carrying shaft, and means arranged on said carrying shaft for holding a sheet of paper.

21. A printing machine comprising a frame, a driving shaft mounted in said frame, a driven shaft mounted in said frame, gears cooperating with said shafts, an arm loosely mounted on said driven shaft, a pair of rollers arranged on said arm, a driven cam operating between said rollers for reciprocating 115 said arm, a casing connected to said frame, a platen shaft arranged in said casing, means operated by said driving shaft for oscillating said platen shaft, a platen, means operated by said platen shaft for reciprocating 120 said platen, a sleeve in said casing, a sheet carrying shaft extending through said sleeve and supported thereby, means operated by said arm for reciprocating said carrying shaft, means operated by said driving shaft for intermittently rotating said carrying shaft, means arranged on said carrying shaft for holding a sheet of paper, and means for feeding printing devices one at a time to printing position.

22. A printing machine comprising a frame, a driving shaft and a driven shaft mounted in said frame, gears communicating with said shafts, an arm loosely mounted on said driven shaft, a pair of rollers on said arm, a driven cam operating between said rollers for reciprocating said arm, a casing connected to said frame, a platen shaft arranged in said casing, means operated by said driving shaft for oscillating said platen shaft, a platen, means operated by said platen shaft for reciprocating said platens, a sleeve in said casing, a sheet carrying shaft extending through said sleeve and supported thereby, means operated by said driven shaft for reciprocating said carrying shaft, means operated by said driving shaft for intermittently rotating said carrying shaft, means arranged on said carrying shaft for holding a sheet, means for feeding printing devices one at a time to printing position, and means controlled by said feeding means for preventing operation of the platen and rotation of the carrying shaft when no printing devices are fed.

23. A printing machine comprising a frame, a driving shaft and a driven shaft mounted in said frame, gears communicating with said shafts, an arm loosely mounted on said driven shaft, a pair of rollers arranged on said arm, a driven cam operating between said rollers for reciprocating said arm, a casing connected to said frame, a platen shaft arranged in said casing, means operated by said driving shaft for oscillating said platen shaft, a platen, means operated by said platen shaft for reciprocating said platen, a sleeve in said casing, a sheet carrying shaft in said sleeve, means operated by said arm for reciprocating said carrying shaft, means operated by said driving shaft for intermittently rotating said carrying shaft, means arranged on said carrying shaft for holding a sheet, means for feeding printing devices one at a time to printing position, means controlled by said printing device feeding means for preventing operation of the platen and rotation of the carrying shaft when no printing devices are fed, and adjusting means for raising or lowering said platen shaft.

24. A printing machine comprising a frame, a driving shaft and a driven shaft mounted in said frame, gears communicating with said shafts, an arm loosely mounted on said driven shaft, a pair of rollers arranged on said arm, a driven cam operating between said rollers for reciprocating said arm, a platen shaft, means operated by said driven shaft for operating said platen shaft, a carrying shaft, means arranged on said carrying shaft for holding a sheet, means operated by said arm for reciprocating said carrying shaft, means driven by said driving shaft for rotating said carrier shaft, a platen, means connecting said platen and said platen shaft

for reciprocating said platen, and adjustable means for raising and lowering said platen shaft.

25. A printing machine comprising a frame, a driving shaft and a driven shaft mounted in said frame, gears communicating with said shafts, an arm loosely mounted on said driven shaft, a pair of rollers arranged on said arm, a driven cam operating between said rollers for reciprocating said arm, a platen shaft, means operated by said driven shaft for operating said platen shaft, a carrying shaft, means arranged on said carrying shaft for holding a sheet, means operated by said arm for reciprocating said carrying shaft, means driven by said driving shaft for rotating said carrying shaft, a plurality of platens, means connecting said platens and said platen shaft for alternately reciprocating said platens, and adjustable means for raising and lowering said platen shaft.

26. A printing machine comprising a frame, a casing mounted on said frame, a platen shaft mounted in said casing, a platen casing, means operated by said platen shaft for reciprocating said platen casing, a sleeve in said casing, a shaft extending through said sleeve and supported thereby, a reel on said last named shaft, means for reciprocating and rotating said last named shaft, a platen arranged in said platen casing, and means controlled by said reel for moving the platen into printing position.

27. A printing machine comprising a frame, a casing mounted on said frame, a platen shaft mounted in said casing, a platen casing, means operated by said platen shaft for reciprocating said platen casing, a sleeve in said casing, a shaft supported by said sleeve and movable therein, a reel on said last named shaft, means for reciprocating and rotating said last named shaft, a platen arranged in said platen casing, means controlled by said reel for moving the platen into printing position, and means for feeding printing devices one at a time to printing position.

28. A printing machine comprising a casing mounted on said frame, a platen shaft mounted in said casing, a platen casing, means operated by said platen shaft for reciprocating said platen casing, a sleeve in said casing, a shaft extending through said sleeve and supported thereby, a reel on said last named shaft, means for reciprocating and rotating said last named shaft, a platen arranged in said platen casing, means controlled by said reel for moving the platen into printing position, means for feeding printing devices one at a time to printing position, and means controlled by said feeding means for preventing operation of the platen shaft and rotation of the second named shaft when printing devices are not being fed.

29. A printing machine comprising a frame, a casing mounted on said frame, a platen shaft mounted in said casing, a platen casing, means operated by said platen shaft for reciprocating said platen casing, a sleeve in said casing, a shaft extending through said sleeve and supported thereby, a reel on said last named shaft, means for reciprocating and rotating said last named shaft, a platen arranged in said platen casing, means controlled by said reel for moving the platen into printing position, means for feeding printing devices one at a time to printing position, means controlled by said feeding means for preventing rotation of the last named shaft and operation of the platen shaft when printing devices are not being fed, and adjustable means for raising or lowering the platen shaft.

30. A printing machine comprising a frame, a driving shaft and a driven shaft mounted in said frame, gears communicating with said shafts, an arm loosely mounted on said driven shaft, a pair of rollers arranged on said arm, a driven cam operating between said rollers for reciprocating said arm, a casing connected to said frame, a platen shaft arranged in said casing, means operated by said driving shaft for oscillating said platen shaft, a platen casing, means operated by said platen shaft for reciprocating said platen casing, a plurality of platens in said platen casing, a carrying shaft mounted in said casing, a reel on said carrying shaft, means operated by said arm for reciprocating said carrying shaft, means for rotating said carrying shaft, and means arranged on said reel for holding a sheet.

31. A printing machine comprising a frame, a driving shaft and a driven shaft mounted in said frame, gears communicating with said shafts, an arm loosely mounted on said driven shaft, a pair of rollers on said arm, a driven cam operating between said rollers for reciprocating said arm, a casing connected to said frame, a platen shaft arranged in said casing, means operated by said driving shaft for oscillating said platen shaft, a platen casing, means operated by said platen shaft for reciprocating said platen casing, a plurality of platens in said platen casing, a carrying shaft mounted in said casing, a reel on said carrying shaft, means operated by said arm for reciprocating said carrying shaft, means for rotating said carrying shaft, means arranged on said reel for holding a sheet, and means connected to said platens and operated by said reel for alternately reciprocating said platens.

32. A printing machine comprising a frame, a drive shaft and a driven shaft mounted in said frame, gears communicating with said shafts, an arm loosely mounted on said driven shaft, a pair of rollers arranged on said arm, a driven cam operating between said rollers for reciprocating said arm, a cas-

ing connected to said frame, a platen shaft arranged in said casing, means operated by said driving shaft for oscillating said platen shaft, a platen casing, means operated by said platen shaft for reciprocating said platen casing, a plurality of platens in said platen casing, a carrying shaft mounted in said casing, a reel on said carrying shaft, means operated by said arm for reciprocating said carrying shaft, means for rotating said carrying shaft, means arranged on said reel for holding a sheet, means connected to said platens and operated by one of said wheels for alternately reciprocating said platens vertically, and means for feeding printing devices one at a time to printing position.

33. A printing machine comprising a frame, a driving shaft and a driven shaft mounted in said frame, gears communicating with said shafts, an arm loosely mounted on said driven shaft, a pair of rollers arranged on said arm, a driven cam operating between said rollers for reciprocating said arm, a casing connected to said frame, a platen shaft arranged in said casing, means operated by said driving shaft for oscillating said platen shaft, a platen casing, means operated by said platen shaft for reciprocating said platen casing, a plurality of platens in said platen casing, a carrying shaft mounted in said casing, a reel on said carrying shaft, means operated by said arm for reciprocating said carrying shaft, means for rotating said carrying shaft, means arranged on said reel for holding a sheet, means connected to said platens and operated by said reel for alternately reciprocating said platens, means for feeding printing devices one at a time to printing position, and means operated by said feeding means to prevent operation of the platen shaft and rotation of said carrying shaft when printing devices are not fed.

34. A printing machine comprising a frame, a driving shaft and a driven shaft mounted in said frame, gears communicating with said shafts, an arm loosely mounted on said driven shaft, a pair of rollers arranged on said arm, a driven cam operating between said rollers for reciprocating said arm, a casing connected to said frame, a platen shaft arranged in said casing, means operated by said driving shaft for oscillating said platen shaft, a platen casing, means operated by said platen shaft for reciprocating said platen casing, a plurality of platens in said platen casing, a carrying shaft mounted in said casing, a plurality of wheels on said carrying shaft, means operated by said arm for reciprocating said carrying shaft, means for rotating said carrying shaft, means arranged on said wheels for holding a sheet, means connected to said platens and operated by one of said wheels for alternately reciprocating said platens, means for feeding printing devices one at a time to printing position, means oper-

ated by said feeding means to prevent opera-
tion of said platen shaft and rotation of said
carrying shaft when printing devices are not
being fed, and adjustable means for raising
5 and lowering said platen shaft.

35. A printing machine comprising a
frame, sheet holding means revolvably mount-
ed in said frame, a platen, means for operat-

ing said platen, means for feeding printing
devices one at a time to printing position, 10
means to shift the sheet circumferentially
relative to said platen, and means to shift
the sheet longitudinally relative to said
platens.

JOSEPH S. DUNCAN.
